SEWING MACHINE

Ignatz Genyk, Vienna, Austria

Application February 7, 1929, Serial No. 338,229
In Austria August 16, 1928

6 Claims. (Cl. 112—258)

This invention relates to sewing machines and consists essentially in that the casing and the work plate are formed of pressed sheet metal as distinguished from cast metal. The casing itself is made in two parts and the machine is so constructed that after unscrewing a few fastening screws one half of the casing may be removed at once so that the entire mechanism located in the casing is freely accessible. The machine according to the invention is simpler and cheaper to manufacture, has besides a greater mechanical strength, has better appearance, and is considerably less in weight than the sewing machines heretofore in use.

The annexed drawings illustrate by way of example a practical embodiment of the invention.

Fig. 1 is a side elevation, partly in section, of the present sewing machine, part of the casing being removed.

Figs. 2, 3 and 4 are sections on the line 2, 2, 3, 3 and 4, 4 respectively of Fig. 1.

Fig. 5 is an inverted plan view of the working plate.

Figs. 6 and 7 are detail side and end views of a part of the mechanism.

Figs. 8 and 9 show two further parts of the link and lever gearing.

As is seen from Figs. 1 and 2, the casing 3 of the top part of the sewing machine consists of two hollow bodies 1 and 2 which are substantially symmetrical and formed of pressed sheet metal such as steel or brass sheet. The casing of the sewing machine may be more or less conventional, with a thick, vertical post standing up from the base or working plate 4 and having a horizontal overhanging arm extending therefrom. Owing to the smooth surface of the two parts of the casing painting or lacquering the same may be dispensed with; if desired these two parts may be coated with nickel or the like by electric deposition. Upon the upper surface of a working plate or base 4 and located at one end there is provided an annular member or ring 5, which is secured to the base by screws 6 or other suitable means. This ring is frustro conical in shape and has an oval base to snugly fit the bottom part of the casing. To this ring the rear half 2 of the casing is secured by welding while the front part 1 of the casing is fastened to the said ring in a readily detachable manner, say by a screw 7. The two parts of the casing are connected with each other by means of strip 8, I shaped in transverse section and curved to snugly fit the edges of the two parts of the casing, such edges engaging into the grooves of the said strip. Prefer-

ably the strips 8 are secured to the stationary half 2 of the casing by welding, but the edges of the removable half 1 of the casing may be pulled away therefrom as occasion demands.

The working plate 4 as well as the supporting body 10 for the actuating mechanism for the shuttle and the cloth feed and with the supporting body 70 for the shuttle and the cloth feed themselves are made of pressed sheet metal and may be connected with each other by welding.

By making the casing in two parts it is possible to journal the main shaft 8 of the machine in a plurality of ball type of bearings, two of which, 11 and 14 are shown. These bearings are mounted in rings 12 rigidly secured to the stationary part 2 of the casing. The removable part 1 of the casing is provided with supporting surfaces on which the rings 12 rest loosely. One or more of the rings 12 may carry screws which serve for securing in position the removable part of the casing.

The inner rings 14 of the ball bearings are capable of being moved along the shaft with moderated friction. For causing them to be revolved together with the shaft the parts fixed adjacent to them to the shaft such as the handle disc 22, the cam 15 and so on are provided with teeth 15 engaging into recesses 16 of the inner rings. After releasing the coupling between the parts such as 15 etc. mounted in the casing and the shaft 8 the shaft may be drawn out of the casing by pulling the handle disc 22, the inner rings 14 remaining in their bearings.

Instead of employing an external fly wheel, a plurality of revolving masses are provided inside the casing and arranged as nearly as possible symmetrically relatively to the bearings, the jar and wear of the latter being greatly reduced thereby. Between the bearings 11 and 14 a disc 15 to which is secured the cam 16, (Fig. 4), is mounted on the shaft 8, such cam serving to actuate the cloth feed lever 11, (Fig. 8); also mounted on shaft 8 between bearings 11 and 14 and rotated by said shaft is the disc 18 to which is secured the eccentric 19 for the eccentric rod 20, (Fig. 9), for actuating the shuttle. Between the disc 18 and the bearing 14 is arranged the clutch 21, serving also as a revolving mass. Outside the bearings 11 and 14 are located the handle discs 22 and the counterweight 23. The handle disc 22 and the revolving disc 15 are in close proximity to the outside of the casing and to the bearing 11 respectively thus holding the shaft 8 in its proper axial position.

In the hub 24 of the clutch mechanism is revolvably mounted the coupling disc 25 while the sleeve 26 is keyed thereto and adapted to move thereon axially. The ring 28 rotatably mounted 5 in the rear part of the casing at 27 serves for shifting the sleeve, such ring engaging into the circumferential groove 29 of the sleeve. The ring carries a handle 30 projecting through a slot 31 of the front part of the casing. A spring 32 10 adapted to engage into suitable recesses in the slot 31 serves to lock the ring 28 in its two extreme positions. The engagement between the sleeve 26 and the disc 25 is brought about by studs 33 parallel to the axis and fast on the sleeve and 15 adapted to engage into holes 34 in the disc. The parts 25 and 26 are journaled on the hub 21 by balls 35, 36; balls 37 are also interposed between the sleeve and the ring 28 and mounted in the intermediate supports 38 rotatable in the ring. 20

The coupling disc 25 serves at the same time for driving the shaft 8 and for this purpose it is provided with a groove 39. The outer wall 40 of this groove is detachably screwed on the body 25 of the disc in order to permit of inserting fillers 41 of leather or the like into the groove for the purpose of increasing the friction of the driving element. The fillers are in the shape of ring segments arranged in a series in the grooves 39. On their outside they have cut into them a groove 42 25 into which is placed the wire rope 43 used for driving and more advantageous than the leather belts heretofore used. This wire rope passes through holes 44, Fig. 3, of an interposed part 45 inserted into a slot of the two parts of the casing and fastened to the stationary part of the casing so that the removable part of the casing may be drawn off such interposed part. The rear part or half of the casing is provided with an opening 46, Fig. 3, closed by cover 72 held in position by screws; through this opening the coupling and actuating mechanism may be inspected. 30

As already stated the revolving disc 15 carries the cam 16 for the cloth feed lever 17. For governing the movement of this lever and therefore 45 also the movement of the cloth feed, this lever is pivoted at 47 to an arm 46 adapted to rock around an adjustable pivot pin. For this purpose the arm 46 is pivoted to an arm 48 loosely mounted on a journal pin 50 together with a disc 49 provided with openings. The said pin 50 50 is carried by a partition 51 screwed to the removable half of the casing. This partition is provided with an eye 52 in which a journal pin 53 is rotatably mounted, which journal pin carries on the one hand a wheel 54 provided with pins and on the other hand a handle 55 provided with a pointer 56 movable along a scale. The wheel 54 cooperates with the disc 49 provided with openings in the manner of a bevel 60 wheel gearing permitting adjustment of the arm 46 by the handle 55.

The handles 55 and 30 of the adjusting mechanism for the cloth feed and for the clutch mechanism may be removed from the studs carrying 65 the same by unscrewing. By removing them and unscrewing the fastening screws 7 and 13 of the removable half 1 of the casing, this half may be readily removed from the stationary half 2.

The parts 17 and 20 of the link and lever gear- 70 ing and the parts associated therewith and transmitting the movement from the main shaft 8 to the cloth feed and to the shuttle journaled between the pairs of points 57, 58 and 59, are of the usual form.

75 Fig. 5 shows the bottom side of the working

plate 4 of the sewing machine with the gearing mounted thereon. It is thought that the description of the arrangement and operation of this gearing may be dispensed with, these being old in the art, but the construction of the parts of the link and lever gearing is novel. Figs. 6 and 7 show by way of example the part journaled between the points 57. It consists of a sleeve 60 of pressed sheet metal. Fillers 61 inserted in the sleeve and having a throughgoing bore 62 serve for journaling. Such bore is provided with an enlargement 63 serving for journaling and on its inside with another enlargement 64 closed by a plug 65; this latter enlargement serves as a receptacle for a lubricant. A cam 66 and two arms 67, 68 are rigidly secured to the sleeve, preferably by welding. Forks cooperating with cams and as shown for instance on the arm 68 and on the cloth feed lever 17, Fig. 8, are provided with linings 69 of bronze or the like for reducing the wear. 10

The shaft 11, Fig. 5, for driving the shuttle is provided with a special lubricating device. This shaft has two bearings 78, 79 with the lubricating points 80, 81 which are connected with the lubricating device located approximately in the middle of the shaft by a longitudinal bore 82 of the shaft and transverse bores 87. The lubricating device consists of two parts 83, 84 enclosing a chamber 85 for the lubricant, one of these parts, 83, is fast on the shaft while the other part 84 may be screwed on the former. These two parts carry packing rings 86 for preventing leakage of the lubricant along the shaft. 15

The part 13 of the machine located beyond the bearing 11 of the main shaft is of known construction and therefore not shown in section. 20

What I claim is:

1. In a sewing machine, a casing for the top part thereof, said casing comprising an overhanging arm and consisting of two substantially symmetrical halves pressed of sheet metal and meeting in a substantially vertical plane, each half of the arm having two edges meeting corresponding edges of the other half, and curved bars which are I-shaped in transverse section, the edges of one of the said halves engaging into one side of the said bars and being permanently fixed thereto, the adjacent edges of the other half of the casing snugly fitting into the other side 45 of the said bar but being removable therefrom. 50

2. In a sewing machine, a casing for the top part thereof, the said casing consisting of two substantially symmetrical halves pressed of sheet metal and meeting in a substantially vertical plane, and means for detachably securing the said two halves to each other, a working plate, an upwardly projecting ring secured to said working plate, said ring engaging and fitting into the bottom part of the said two part casing, one half 55 of the said casing being permanently secured to the said ring, the other half being detachably secured to the said ring. 60

3. In a sewing machine a casing for the top part thereof, said casing consisting of two substantially symmetrical halves pressed of sheet metal, a working plate, a ring secured to said working plate, said ring engaging and fitting into the bottom part of the said two part casing, one of the halves of the casing being welded to said ring, the other half of the casing being detachably secured to said ring, a main shaft of the sewing machine, bearings for said main shaft, said bearings being permanently secured to one half only 65 70 75 80

of said casing, and snugly fitting the other half of said casing.

4. In a sewing machine a casing for the top part thereof said casing consisting of two substantially symmetrical halves pressed of sheet metal, a working plate, a ring secured to said working plate, said ring engaging and fitting into the bottom part of the said two part casing, one of the halves of the casing being welded to said ring, the other half of the casing being detachably secured to said ring, in combination with the main shaft of the sewing machine, ball bearings for said main shaft, said bearings being permanently secured to one half only of the casing, and snugly fitting the other half of said casing, said ball bearings comprising inner rings longitudinally slidable relatively to the said main shaft, and means for releasably coupling said inner rings with the said main shaft for rotation, the last named means comprising elements located adjacent to the said inner rings, the said inner rings and elements adjacent thereto being provided with clutching parts engaging with each other.
5. In a sewing machine a casing for the top part thereof, said casing consisting of two substantially symmetrical halves pressed of sheet metal, a working plate, a ring secured to said working plate, said ring engaging and fitting into the bottom part of the said casing, one of the halves of the casing being welded to said
- ring, the other half of the casing being detachably secured to said ring, in combination with a main shaft, ball bearings for said main shaft, said bearings being permanently secured to one half only of the casing, and snugly fitting the other half of said casing, said ball bearings comprising inner rings longitudinally slidable relatively to the said main shaft, and means for releasably coupling said inner rings with the said main shaft for rotation, the last named means comprising elements located adjacent to the said inner rings, the said inner rings and elements adjacent thereto being provided with clutching parts engaging with each other.
6. In a sewing machine, a casing for the top part thereof, said casing consisting of two substantially symmetrical halves pressed of sheet metal having opposed slots therein, a main shaft, journaled in the said casing, a driving pulley mounted on the said main shaft, a driving belt for actuating the said pulley, an interposed part engaging the said slots and secured to one of the halves of the casing, said interposed part having openings for the said belt to pass through.
